UNITED STATES PATENT OFFICE.

FRANCIS WARE, OF BOSTON, MASSACHUSETTS.

TELEPHONE MOUTH AND EAR PIECE.

SPECIFICATION forming part of Letters Patent No. 297,732, dated April 29, 1884.

Application filed January 14, 1884. (No model.)

To all whom it may concern:

Be it known that I, FRANCIS WARE, a citizen of the United States, and a resident of the city of Boston, county of Suffolk, and State of 5 Massachusetts, have invented certain new and useful Improvements in Telephone Mouth and Ear Pieces, of which the following is a specification.

My invention relates to detachable mouth or 10 ear pieces for telephonic transmitters and receivers; and it has for its object to increase the volume of sound which, in the utterance of speech, reaches the diaphragm in telephonic transmitters, without the inconveniences which 15 arise from the use of mouth-pieces which compel the speaker to bring his mouth in close proximity to the diaphragm, and to concentrate the sound-waves of a receiving-instrument upon the ear of the listener, as will be 20 more particularly set forth hereinafter.

My invention differs from the ordinary speaking or listening tubes which are sometimes used in connection with telephones, in that it acts like a spherical reflector, concentrating the sound-waves upon the diaphragm or the ear without that absorption which results from the multiplex reflections from the walls of the tube.

It also has for its object to prevent the deposition of the moisture from the breath of the speaker upon the diaphragm.

My invention consists in a detachable mouth or ear piece formed of two hemispherical sections united by a conical section, which connects the base of the larger of the two hemispheres with apex of the smaller.

It further consists in a sound-opening formed in a section of the larger hemisphere of the mouth or ear piece, preferably on the side 40 thereof, whereby its position may be adjusted by turning the said hemisphere on its support in the connecting-cone.

It further consists in means for conveniently attaching or detaching the mouth or ear piece 45 to the telephone-case.

It further consists in the several details of construction, as more particularly pointed out hereinafter.

Referring to the drawings forming part of the 50 specification, Figure 1 is a perspective showing my invention attached to an ordinary box-

transmitter. Fig. 2 is a section of the same. Fig. 3 is a rear view of the attachment.

A semi-spherical shell, B, made of any suitable material, preferably metal, is provided near its base with two lugs projecting into the plane of said base, so as to be flush therewith. One of the lugs, C, has a longitudinal slot, and the other, D, has a lateral slot. To the perforated apex of the hemisphere B is secured the smaller 60 end of a hollow frustum of a cone, E. The larger end of said cone is provided with a rim, e, into which fits and is frictionally held the base of a hollow hemisphere, F. By thus connecting the larger hemisphere with the cone, 65 the same may be turned in its bearing and a sound-opening, G, cut into said hemisphere, may thereby be adjusted to any convenient position for speaking or listening.

This instrument is secured to a telephone-case, A, by means of two screws or studs, b c, fixed to the face thereof and engaging the slots in the lugs C D. By having the slot in one lug longitudinal and in the other lateral, the instrument may be easily and quickly attached to 75 the telephone-box by slipping the lug C onto the stud b, and then turning the instrument in position, so that the slot in lug D engages stud c.

It will be understood that the case A is here 80 shown as representing any transmitter or receiver, and the means of attaching the instrument to the case may be varied to suit the different forms of the telephones. If used as a transmitter, the sound-waves entering the outer hemisphere, F, through the opening G will be 85 reflected and concentrated more or less directly upon the diaphragm of the telephone, and any moisture from the breath of the speaker will be precipitated into the lower part of the cavity formed by parts E and F. If used as 90 a receiver, the sound-waves will be reflected into the outer hemisphere, and from the walls thereof they will be concentrated upon the ear of the listener.

What I claim is—

1. A mouth or ear piece for telephones, consisting of two hemispherical sections joined by a conical section, substantially as described.
2. A mouth or ear piece for telephones, consisting of two hemispherical sections joined by a conical section, the outer hemisphere having an opening in its side.

3. In a mouth or ear piece for telephones, the combination, with the flaring connecting-piece E, of the hemispherical piece F, having an opening, G, the construction being such that the latter may be turned upon the former, to bring the opening into any desired position.

4. The combination, with the case of a telephone, of a mouth and ear piece consisting of two hemispherical sections joined by a conical

section, and means for attaching the same to the telephone-case, as set forth.

In testimony whereof I have signed my name to this specification in the presence of two subscribing witnesses.

FRANCIS WARE.
